TOY RAILROAD HAND CAR

Robert Genin, Scarsdale, N.Y., assignor to Child Guidance
Toys Inc., Bronx, N.Y., a corporation of New York

Filed July 18, 1967, Ser. No. 7,845

Term of patent 14 years

Int. Cl. D21—02

U.S. Cl. D34—15

Fig. 1.

Fig. 2.

FIG. 1 is a perspective view of my design for a toy railroad hand car whose body is transparent to reveal the inner working gears;

FIG. 2 is a plan view of the hand car;

FIG. 3 is a front end view; and

FIG. 4 is a rear end view.

I claim:

The ornamental design for a toy railroad hand car, substantially as shown and described.
